(57) **CLAIM**

The ornamental design for a pet toy, as shown and described.

DESCRIPTION

FIG. 1 is a perspective view of the pet toy;

FIG. 2 is a left side view of the pet toy;

FIG. 3 is a right side view of the pet toy;

FIG. 4 is a top plan view of the pet toy; and,

FIG. 5 is a bottom plan view of the pet toy.

The broken lines illustrate portions of the pet toy that form no part of the claimed design.
